UNITED STATES PATENT OFFICE

2,594,416

SUCTION CLEANER

Dale C. Gerber, North Canton, and Frank A. Martin, Akron, Ohio, and Eugene L. Snyder, St. Petersburg, Fla., assignors to The Hoover Company, North Canton, Ohio, a corporation of Ohio

Application September 10, 1947, Serial No. 773,194.

8 Claims. (Cl. 183—37)

1

This invention relates to a suction cleaner and more particularly to the construction of the casing for a tank type cleaner.

It is an object of the invention to provide a new and novel suction cleaner casing. Another object is to provide a cleaner casing having a skeleton frame to support the relatively heavy parts of the suction cleaner mechanism. A further object is to provide a skeleton frame for a cleaner casing having a cover therefor of metallic and non-metallic materials. Another object of the invention is to provide a cleaner casing having a skeleton frame and a non-metallic cover therefor which is formed directly about the frame and attached thereto. Other objects and advantages of the invention will be apparent from the following specification and drawings wherein:

Figure 1 is a sectional view of the cleaner casing;

Figure 2 is a section along the line 2—2 in Figure 1;

Figure 3 is a section along the line 3—3 in Figure 1;

Figure 4 is a perspective view of the skeleton frame construction; and

Figure 5 is a perspective view of the casing with certain parts removed.

The embodiment of the invention herein disclosed comprises a casing 10 having a skeleton frame including a top side member 11 of channel shape and two angle shaped bottom side members 12 and 13. The forward ends of the side members are welded to the walls of recesses 14, 15, and 16 in a flange 17 of an L-shaped front end member 18 and lie flush with the vertical wall 19, while the rear ends of the side members extend beyond an L-shaped rear end member 20 and are secured thereto in walls of recesses similar to those in the front end member. Between the end members 18 and 20 is a transverse member 22 which is secured to the side frame members 11, 12, and 13 and forms with the end members the frame structure for a motor chamber 23 and a suction chamber 24.

The cover for the skeleton frame includes a 45 metallic bottom plate 25 having a flat portion 26 and upstanding marginal flanges 27 and 28 to cover the area between the bottom side frame members 12 and 13 and the remaining portion of the frame is enclosed by a non-metallic cover 30. The cover 30 is attached to the frame by heating a sheet of non-metallic material and then placing it about the frame and forming it to the contour of the frame. Thereafter the marginal edges 31—31 of the cover 30 are placed between the 55

2

side frame members 12 and 13 and the bottom plate 25, and the latter and the cover 30 are secured to the side frame members 12 and 13 by means of a plurality of rivets 33.

The opposite ends of the casing 10 are closed by a suction end cap 35 having an inlet 36, and by an exhaust end cap 37 having an outlet 38. A suitable latch 39 removably attaches the end cap 35 to the casing 10, while the rear end cap 37 is secured by a screw 40 threaded into a bracket 41 carried by the top side member 11, and another screw 42 is threaded into a bracket 43 mounted in a recess 44 in the end frame member 20.

Disposed within the suction chamber 24 is a 15 dirt filtering bag 45 supported at its open end by an annular flange 46 of a bag supporting ring 47 which is secured to the front end member 18 by unshown bolts extending through openings 49 in the vertical wall 19 of the front end member.

20 The rear end 50 of the bag 45 is supported by a plurality of arms, two of which are identified at 51 and 52, and a bail 53 connects the arm 52 to a bag shaking mechanism indicated generally at 54 of the type disclosed in the application of 25 Louis E. Segesman, Serial No. 599,147, filed June 13, 1945 now Patent No. 2,498,098. The bag shaking mechanism is actuated by a manually operated lever 55 which is pivotally mounted in the opening 56 of the bottom plate.

30 In operating the bag shaking mechanism, the front end cap 35 is removed and the cleaner casing is up-ended to place the vertical wall 19 of the front end member 18 on a supporting surface, and a piece of paper is preferably placed beneath the end frame member 18 to collect the dirt removed from the bag. Pressure is applied to the bag shaking lever 55 to operate the bag shaking mechanism 54 in the manner described in said pending application and the dirt is removed from the bag and drops onto the paper. During the bag shaking operation the pedal 55 pivots in the opening 56 of the metal cover plate 25 and the force applied to the pedal is transmitted to the metal cover plate 25 so that the non-metallic cover 30 is not subjected to the relatively large force applied to the bag shaking pedal 55.

Disposed in the motor chamber 23 is a motor-fan unit 60, the forward end of which seats in a resilient ring 61 mounted upon the intermediate member 22. The rear end of the motor-fan unit is mounted in a resilient ring 63 which seats in a spider member 64 attached to the vertical wall 65 of the rear end member 20 by bolts extending through openings 66 in the vertical wall 65.

In attaching the intermediate member 22 and

spider 64 to the side frame member 11, 12, and 13, the vibration of the motor-fan unit is not transmitted to the non-metallic cover 30.

Openings 70 are provided in the top side frame member 11 for receiving bolts 71 to attach a handle 72 to the frame member so that the weight of the cleaner when it is lifted off the floor is transmitted to the skeleton frame structure. A boss 74 is formed on the top frame member 11 to which a switch 75 is mounted. Holes 76 are provided in the metal bottom plate 25 for attaching to the latter a pair of cleaner supporting skids 77.

We claim:

1. In a suction cleaner casing, a skeleton frame having a plurality of spaced side members extending longitudinally of the casing, an end frame member attached to opposite end portions of said side members to space and support the latter, an intermediate transverse member between said end frame members and attached to said side frame members to form a motor chamber and dust chamber, a cover encircling said frame members to enclose the latter, and an end cover for each end of said frame to complete the cleaner casing.

2. In a suction cleaner casing, a skeleton frame having a plurality of spaced side members, one of said members extending along the top of the casing, an end frame member attached to opposite end portions of said side members to space and support the latter, means on said top member for supporting a cleaner carrying handle and an electric switch, a cover encircling said frame members to enclose the latter, and an end cover for each end of said frame to complete the cleaner casing.

3. In a suction cleaner casing, a skeleton frame having a plurality of spaced side members extending longitudinally of the casing, an end frame member attached to opposite end portions of said side members to space and support the latter, one of said end frame members having means to support a motor, an intermediate transverse member between said end frame members and attached to said side frame members to form a motor chamber and dust chamber, a cover encircling said frame members to enclose the latter and attached thereto, and an end cover for each end of said frame to complete the cleaner casing.

4. In a suction cleaner casing, a skeleton frame having a plurality of spaced side members extending longitudinally of the casing, an end frame member attached to opposite end portions of said side members to space and support the latter, an intermediate transverse member between said end frame members and attached to said side frame members to form a motor chamber and dust chamber, said intermediate transverse member and one of said end members having means to support a motor therebetween, a cover encircling said frame members to enclose the latter and attached thereto, and an end cover for each end of said frame to complete the cleaner casing.

5. In a suction cleaner casing, a skeleton frame having a plurality of spaced side frame members, transverse members connected with said side members to form a self supporting frame structure, a filter within the confines of said

frame, a cover for said frame including metallic and non-metallic portions cooperating to enclose said frame, filter shaking mechanism mounted on said metallic cover portion, and cleaner casing supporting means also mounted on said metallic cover portion, whereby said non-metallic cover portion is not subjected to the stresses applied to said bag shaking mechanism and casing supporting means.

6. In a suction cleaner casing, a skeleton frame having a plurality of spaced side members extending longitudinally of the casing, an end frame member attached to opposite end portions of said side members to space and support the latter, an intermediate transverse member between said end frame members and attached to said side frame members, said intermediate transverse member and one of said end frame members having means to support a motor therebetween, and a cover for said frame including metallic and non-metallic portions cooperating to enclose said frame.

7. In a suction cleaner casing, a skeleton frame having a plurality of spaced side members extending longitudinally of the casing, transverse members connected with said side members to form a self supporting frame structure, a filter within the confines of said frame, a cover for said self supporting frame and including metallic and non-metallic portions cooperating to enclose said frame, filter shaking mechanism mounted on said metallic cover portion independently of said non-metallic cover portions whereby said non-metallic cover portion is not subjected to the stresses applied to said bag shaking mechanism on said metal cover portion.

8. In a suction cleaner casing, a skeleton frame having a plurality of spaced side members extending longitudinally of the casing, transverse members connected with said side members to form a self supporting frame structure, a filter within the confines of said frame, a cover for said self supporting frame to enclose the latter and said filter, and filter shaking mechanism movably mounted on said cover and connected to said filter.
